GUSTAVE WENZELMANN, OF GALESBURG, ILLINOIS.

WRINGER ATTACHMENT FOR WASHING-MACHINES

1,123,447.

Specification of Letters Patent.

Patented Jan. 5, 1915.

Application filed October 23, 1911. Serial No. 656,157.

To all whom it may concern:

Be it known that I, GUSTAVE WENZELMANN, a citizen of the United States, and residing at Galesburg, in the county of Knox and State of Illinois, have invented a new and useful Improvement in Wringer Attachments for Washing-Machines, of which the following is a complete specification.

The main objects of this invention are to provide improved mechanism for mounting wringers on washing machines; to provide mechanism whereby the wringer is adapted to be supported in one position to wring from the washing machine to a tub, and in another position to wring from the first tub to a second tub or vice versa; to provide mechanism adapted to swing the wringer through a vertical arc from one position to another; to provide mechanism for operating the wringer in any of its adjusted positions; to provide improved means for reversing the wringer; and to provide a strong and simple device by means of which the wringer may be quickly and easily moved from the washing machine to the tubs and vice versa.

A specific embodiment of the invention is illustrated in the accompanying drawings, in which:

Figure 1 is a side elevation of a washing machine with the means for mounting and operating the wringer embodied in this invention attached thereto. Fig. 2 is a side elevation of the gear bracket or frame. Fig. 3 is an end elevation of the gear bracket or frame. Fig. 4 is a top plan view of the washing machine and its attachments, with the platform removed. Fig. 5 is a fragmentary section taken on line 5—5 of Fig. 4. Fig. 6 is a fragmentary view of the reversing mechanism for the wringer. Fig. 7 is a front elevation of the same.

In the construction shown the washing machine bench or frame comprises front legs or posts 1 and rear legs or posts 2, which are secured together by longitudinal rails or side members 3 and end members 4. On the side members 3 is a platform 5 on which the washing machine 6 and tub 7 are supported. A tub 8 is suitably supported at the front end of the frame.

The wringer 9 is so mounted that it is adapted to be swung through a vertical arc from its forward position and oppositely.

For this purpose a pair of vertical swinging arms 10 and 11 adapted to swing in

parallelism are pivoted at each side of the frame and support the wringer. One of the arms 10 is pivoted at its lower end on the outer end of the clutch shaft 12, and the other arm 10 is pivoted on a stud pin 13 at the other side of the frame and in alinement with the shaft 12. Both of the arms 11 are pivoted at their lower ends on stud pins 14 carried on the frame members 3 forwardly of the arms 10. The upper ends of the arms 10 and 11 of each pair are connected by a horizontal supporting bar 15 which is pivoted to said arms and holds their upper ends the same distance apart as their lower ends. 70

The wringer base 16 is rigidly secured at its ends on said bars 15, and in the forward position of said arms is adapted to rest on the tops of the posts 1, and in the rearward position of said arms is adapted to rest on a ledge 17 on the washing machine, as is shown more clearly in full and dotted lines respectively in Fig. 1.

A gear bracket or frame 18 is rigidly secured on the inner side of one of the side frame members 3, and the clutch shaft 12 is journaled at its inner end in a bearing 19 in said bracket and at its outer end in a suitable bearing 20 on the under side of said frame member 3. 85

Loosely mounted on the shaft 12 are the gears 21 and 22, which have clutch members 23 and 24 respectively on their adjacent faces. Slidably mounted on the shaft 12, intermediate the gears 21 and 22, is the clutch member 25 adapted to lock either of said gears to the shaft. On the outer end of the shaft 12 is a sprocket wheel 26 in alinement with a larger sprocket wheel 27 on the wringer shaft 28, and a sprocket chain 29 is carried on said sprocket wheels and acts to drive the wringer in either direction from the shaft 12.

A shaft 30 is journaled in bearings 31 and 32 respectively on the bracket 18 and the frame member 3, intermediate the shaft 12 and the washing machine. Gears 33 and 34 are rigidly secured on the shaft 30 in alinement with the gears 21 and 22. The gear 33 is out of mesh with the gear 21, and the gear 34 is in mesh with the gear 22. A drive pulley 35 is carried on a stud shaft 36 which is journaled in a bearing 37 in the bracket 18, and on the inner end of said stud shaft is a pinion 38 which meshes with the gears 21 and 33. 110

On the outer end of the shaft 30 is a pin-

ion 39 which meshes with a pitman gear 40 journaled on the frame member 3. A rock shaft 41 is journaled at the rear of the frame and is provided at one end with an arm or lever 42 which is connected with the pitman gear 40 by means of a bar 43. An arm 44 is rigidly secured on the other end of the shaft 41 and is connected at its upper end to the operating mechanism 45 of the washing machine by means of a connecting link 46.

For the purpose of controlling the direction in which the wringer is operated, shafts 47 and 48 are journaled in the lower ends of the posts 1 and 2 respectively, and are provided on their ends, at the outer sides of said posts with treadles 49. Each shaft 47 and 48 is provided with an upwardly directed lever 50, which levers are connected together by a bar or rod 51. Rigidly secured on and extending upwardly from the bar 51 is a bar 52 which is pivotally connected at its other end to one arm of a bell-crank lever 53. The bell-crank lever is pivoted to the bracket 18, and its other arm is provided with a fork 54 in engagement with the clutch member 25 and adapted to shift the same.

The operation of the construction shown is as follows: The shaft 36 is driven from any suitable source of power and operates the washer mechanism through the intermediary of the gears 38, 33, 39 and 40 and the connections with the rock shaft 41. If it is desired that the washer shall remain idle while the shaft 36 is in operation, the link 46 is disconnected from the washing mechanism 45. If the drive pulley 35 is rotated in the direction indicated by the arrow in Fig. 1, and the clutch member 25 is thrown into engagement with the clutch member 23, the gear 21 is locked to the shaft 12 and the wringer is operated in a direction to run the clothes from the rinsing tub 7 to the bluing tub 8, if the wringer is in the position shown in full lines in Fig. 1, or to run the clothes from the washer 6 to the rinsing tub 7, if the wringer is in the position shown in dotted lines in Fig. 1. When it is desired to run the clothes from the tub 8 the clutch member 25 is shifted into engagement with the clutch member 24, thereby locking the gear 22 to the shaft 12, which shaft is then driven in the opposite direction through the gears 33 and 34, thereby reversing the operation of the wringer. A tray may be placed on the tub 7 to catch the clothes, or said tub may be replaced by a basket.

It will be readily understood that when 60 the wringer is wringing from the tub 7 to the tub 8, or from the tub 8 the washer may be in operation if desired.

It will also be readily understood that the wringer may be easily and quickly changed 65 from the position shown in full lines in Fig. 1, to that shown in dotted lines by simply swinging the arms 10 and 11 through a vertical arc, thereby practically eliminating all friction in moving the wringer, and without 70 in any way disturbing the operating mechanism. The wringer, because of said pairs of arms swinging in parallelism always assumes a horizontal position regardless of the position of said arms, and is always rigidly 75 supported when in operative position.

Obviously many details of the construction shown and described may be varied or omitted without departing from the scope of the claims.

I claim:

1. In combination with a frame which includes side frame-rails, a shaft supported transversely of one of said rails, a sprocket wheel on said shaft, swinging arms, 10, one 85 of them pivoted on said shaft, the other being pivoted on a stud-pin in line with said shaft, stud-pins supported transversely of said rails, swinging arms, 11, pivoted on said stud-pins, a horizontal arm pivoted to 90 the upper ends of each couple 10, 11, of said swinging arms, a support carried on said horizontal arms, a shaft supported thereby, a sprocket wheel on said shaft, and a chain embracing said wheel and the one first 95 recited.

2. In combination with a frame which includes side frame-rails, a shaft supported transversely of one of said rails, means for supporting said shaft, a sprocket wheel on 100 said shaft, stud-pins supported transversely of said rails, swinging arms, 11, pivoted on said pins, swinging arms, 10, one of them pivoted on the shaft above recited, an arm 10 and an arm 11 constituting a couple, 105 a horizontal arm pivoted to the upper ends of each couple, a shaft supported thereby, a sprocket wheel on said shaft, a chain embracing said wheel and the one first recited, and means for reversing the direction of 110 motion of said shafts.

In testimony whereof I have hereunto subscribed my name in the presence of two witnesses.

GUSTAVE WENZELMANN
